UNITED STATES PATENT OFFICE.

LEOPOLD BLATTMACH'R, OF BROOKLYN, NEW YORK.

SURGICAL BRACE.

SPECIFICATION forming part of Letters Patent No. 431,797, dated July 8, 1890.

Application filed April 2, 1890. Serial No. 346,351. (No model.)

To all whom it may concern:

Be it known that I, LEOPOLD BLATTMACH'R, of Brooklyn, in the county of Kings and State of New York, a citizen of the United States, 5 have invented certain new and useful Improvements in Surgical Braces, of which the following is a specification.

This invention relates to an improved surgical brace of that class which is used for 10 strengthening the muscles of the leg, so as to facilitate the walking of persons afflicted with lame or weak limbs, the improvements being specially designed with a view to facilitate the detaching of the shoe from the brace and 15 of adjusting the brace into proper position relatively to the ankle.

The invention consists of a surgical brace for strengthening the muscles of the leg, said brace being applied in the usual manner to 20 the leg and provided below the knee-joint with straps that extend from the knee-joint at both sides of the leg to the ankle-joint, said straps being provided with a recess at the lower ends and with a spring-clasp that serves to engage 25 in a detachable manner the forked ends of a yoke-shaped strap attached to the sole of the shoe, said forked ends being provided with fixed pins for engagement, respectively, with the recessed and perforated ends of the side 30 straps and spring-clasps.

The invention consists, secondly, of a curved rear brace that connects the side straps of the leg, said brace being riveted to one strap and adjusted at its opposite end by a slotted 35 extension, and a clamping-screw on the other strap, as will be fully described hereinafter, and finally pointed out in the claims.

In the accompanying drawings, Figure 1 represents a side elevation of my improved 40 surgical brace for legs. Figs. 2 and 3 are a detail side view and vertical transverse section of one of the side straps of the brace, showing the connection of the side strap with the strap applied to the shoe; and Figs. 4, 5, 45 and 6 show details of the curved rear brace, by which the side straps of the legs are connected.

Similar letters of reference indicate corresponding parts. 50 In the drawings, A represents a surgical brace of that class which is applied to the leg

for strengthening the muscles of the same and facilitating the walking of persons having weak or lame legs. The brace is applied by leather straps *a a'* to the leg in the usual 55 manner, the strap *a* being applied, respectively, to the thigh, and the strap *a'* to the calf of the leg, as shown in Fig. 1. The side straps *b b'* of the thigh and calf are connected by knee-joints *d*, which are located at both sides 60 of the knee. The lower ends of the straps *b'* at both sides of the calf are connected near the ankle by pivot-joints *e* with a yoke-shaped strap *f*, which is attached transversely to the sole of the shoe. Heretofore the ankle-joint 65 *e* was made in the nature of a permanent pivot-connection, which prevented the detaching of the shoe from the side straps *b' b'*, so that when the muscles of the foot were strained and tired considerable pain was 70 caused owing to the inability of removing the shoe and giving relief to the strained muscles of the foot and leg. For the purpose of overcoming this defect the ankle-joint is made in the nature of a detachable joint, and constructed in the following manner: The lower 75 ends of the side straps *b'* are recessed at *b²*, so as to engage pins *e'*, which are attached to the upper ends of the yoke-shaped strap *f*, attached to the shoe, said recessed ends *b²* being inserted between the upper ends of the strap *f*, and a keeper *f'*, attached to each end of the same. To each side strap *b'* is riveted 80 a spring-clasp *g*, the lower enlarged end of which is provided in front of the recessed end 85 of the strap *b'* with a slotted opening or eye *g'*, as shown in Fig. 2, that passes over the end of the locking-pin *e'* of the strap *f*, so as to engage said pin in connection with the recessed end of the strap *b'*. By moving then a 90 metallic sleeve or loop *g²* in downward direction over the spring-clasp *g* until it abuts against the enlarged edge of the same, the parts of the ankle-joint *e* are firmly held in position, so as not to get accidentally detached 95 from each other, as shown in Fig. 3.

Whenever it is desired to give relief to the foot without taking off the entire brace—as, for instance, after a long walk or when the party wearing the brace has to sit for some 100 time, the sliding loop *g²* is moved upward away from the ankle-joint *e*, and the locking-

spring *g* released from the pin, so that first the side strap *b'* at one side is detached from the shoe-strap *f*. This is repeated at the opposite side of the brace, so that both side straps *b'* are disconnected from the shoe-strap *f* and thereby the required relief given to the muscles of the leg. This detachable joint renders the leg-brace more comfortable to the wearer, as he can always, by an easy manipulation, detach the shoe from the brace when resting, so as to enable him to give relief to the strained and fatigued muscles of the leg.

The second part of my improvement consists of a semicircular rear brace *h*, which is applied to the middle part of the side straps *b'* of the calf, by which brace said straps are rigidly connected after the brace is applied to the leg. For this purpose one end of the semicircular brace *h* is permanently riveted to one of the side straps *b'*, while the opposite end of said brace is provided with a slotted extension *h'* that is arranged at right angles to the semicircular portion that extends around the back of the calf and attached by a clamping-screw *h*² to the opposite side strap *b'*. The clamping-screw *h*² passes through one of several holes of the side strap *b'*. By clamping the rear brace *h* in higher or lower position to the side strap, the ankle-joint *e* and shoe-strap *f* are raised or lowered at one side and set to the required position on the foot and ankle.

Having thus described my invention, I claim as new and desire to secure by Letters Patent—

1. The combination, with the side straps, of a surgical leg-brace, said straps being recessed at the lower ends, spring-clasps ap-

plied to said straps and having enlarged and slotted ends in front of the recessed ends of the straps, and a yoke-shaped strap attached to the shoe and provided with keepers at the ends, and with fixed transverse pins passing through said keepers, said pins and keepers interlocking with the recessed and slotted ends of the side straps and spring-clasps, substantially as set forth.

2. The combination, with the side straps, of a surgical leg-brace, said side straps being recessed at the lower ends and provided with spring-clasps having slots in front of said recessed ends, a yoke-shaped strap applied to the shoe and having keepers at the upper ends and fixed transverse pins passing through said keepers, and a sliding sleeve or loop for retaining the interlocking parts of the side straps and shoe-straps in position, so as to produce a detachable ankle-joint, substantially as set forth.

3. The combination, with the side straps, of a surgical brace applied to the leg, of a semicircular rear brace extending around the calf, said brace being rigidly attached to one of the side straps and provided with a slotted extension at the other end, and a clamping-screw for attaching said brace at a higher or lower point to the opposite side strap, substantially as set forth.

In testimony that I claim the foregoing as my invention, I have signed my name in presence of two subscribing witnesses.

LEOPOLD BLATTMACH'R.
